GLOW DISCHARGE RELAY

Harry C. Thompson, East Orange, N. J., assignor
to General Electric Company, a corporation of
New York

Application December 7, 1931, Serial No. 579,481

11 Claims. (CL 256—41.5)

My invention relates to means for controlling electric circuits and more particularly, to means employing glow discharge tubes in a relay circuit.

5 It has for one of its objects to provide an improved circuit utilizing electron discharge devices of the glow discharge type whereby extremely sensitive operation may be had in response to slight variations in a predetermined primary variable. Such a primary variable may, for example, comprise any desired variable electrical condition, intensity of light or other variable in response to which it is desired to effect a desired control operation.

15 Another object of my invention is to provide a circuit arrangement including a plurality of electron discharge devices of the gaseous glow type in which in response to a primary variable, a change in distribution of voltages on said discharge devices is brought about, causing said devices to break down in rapid succession, thereby to cause an instantaneous change in current in the circuit which may be utilized to effect any desired control operation.

25 The novel features which I believe to be characteristic of my invention are set forth with particularity in the appended claims. My invention itself, however, both as to its organization and method of operation, together with further objects and advantages thereof, will be better understood by reference to the following description taken in connection with the accompanying drawing in which Figs. 1 and 2 represent control circuits actuated by a light source; Figs. 3 and 4 represent other applications of my invention which may be used to indicate the movement of a body past the control circuit; Fig. 5 represents an embodiment of my invention which may indicate the presence of an alternating potential on conductors in the proximity of the control circuit; and Fig. 6 is a still further embodiment of my invention in which the control circuit is actuated by high frequency currents.

Referring to Fig. 1 of the drawing, I have illustrated therein a control circuit including two glow discharge devices which may be of the gaseous discharge type having two assymmetric electrodes. Glow discharge devices 1 and 2 are connected in series with the winding of relay 3 and the secondary winding of transformer 4. Transformer 4 is connected to a suitable alternating current line 5 to impress an alternating potential across the glow discharge devices 1 and 2. Glow discharge device 1 has a light-sensitive cell 6 connected in parallel thereto. The contacts of

relay 3 may be connected to control a circuit such as indicated by the lamp load 7.

In operation, the alternating current voltage impressed across glow discharge devices 1 and 2 by the transformer 4 should be insufficient to cause the discharge devices to glow when there is an equal division of voltage across them but sufficient to maintain the glow discharge when started. In other words, the peak voltage of the alternating potential must be less than twice the breakdown voltage and greater than twice the minimum glow voltage of a single glow discharge device. The light-sensitive cell 6, which is in parallel to glow discharge device 1, normally has a high impedance so that the potential across the discharge devices is substantially equally divided. If light from a source such as is indicated at 8 is allowed to impinge upon the light-sensitive cell 6, the impedance of the light-sensitive cell is reduced so that the voltage across glow discharge device 2 increases and a corresponding decrease in the voltage across glow discharge device 1 occurs during the half-cycle when the alternating current potential across the light-sensitive cell is in the proper direction. This increase in voltage across glow discharge device 2 is sufficient to cause it to glow, whereupon the voltage across this device drops so that a greater part of the line voltage appears across glow discharge device 1 which in turn also glows, thereby allowing current to flow through both of the glow discharge devices. This current is sufficient to operate the relay 3, thereby energizing the circuit to be controlled which may be, for example, a lamp load shown at 7. This control circuit energizes the relay as long as light from a source 8 impinges on the light-sensitive cell 6. When the light no longer impinges upon the light-sensitive cell 6, the glow through the discharge devices 1 and 2 ceases because the glow breaks or ceases during each cycle of the alternating current. In this manner it will be apparent the control circuit may be used to energize or de-energize the circuit to be controlled.

If desired, the arrangement in Fig. 1 may be operated from a direct current source. If the leads 5 are connected to a direct current line in which an interrupter has been inserted to provide pulsating direct current, the arrangement in Fig. 1 may be used without further modification.

Another arrangement of Fig. 1 may be obtained by removing the transformer 4 and connecting the relay coil 3 and the glow discharge devices 1 and 2 to the leads 5. The leads 5 may

then be connected to a source of direct current potential of proper polarity insufficient to cause the discharge devices to glow, but sufficient to maintain the glow when started. In such an arrangement the presence of light upon light-sensitive cell 6 causes the glow discharge cells to glow in succession and the relay to be operated. The glow discharge devices continue to glow even when the light no longer impinges upon light cell 6, because the glow potential does not go through a negative cycle as was the case in the alternating current arrangement. To stop the glow of the discharge devices and to release the relay, the direct current must be interrupted by a switch. In some applications this direct current arrangement may be highly desirable, where it is desired to arrange an alarm which remains actuated until an operator manually releases it.

Referring to Fig. 2, I have illustrated therein a pair of glow discharge devices 11 and 12 connected in series with the secondary winding of transformer 13 and the winding of relay 14. The capacities of the electrodes of glow discharge devices are balanced by means of capacitors 15 and 16 which are connected in parallel with the respective glow discharge devices. Glow discharge device 11 has a light-sensitive cell 17 connected in parallel thereto and glow discharge device 12 has a resistance 18 connected in parallel thereto to balance the photo-electric current which is flowing through the light-sensitive cell 17 when light from source 20 impinges upon the cell. Relay 14 may have a resistance 19 connected in parallel thereto to prevent actuation of the relay by the leakage current of light-sensitive cell 17. An alternating current potential insufficient to cause glow is impressed across glow discharge devices 11, 12 by means of the transformer 13 which is connected to an alternating current line 9. The relay 14 may be used to control any load circuit which is represented by the lamp load 10.

The combination of the glow discharge devices 11 and 12, the capacitors 15 and 16, and the light-sensitive cell 17, and resistor 18 constitutes a balanced bridge circuit which becomes unbalanced when light from source 20 no longer impinges upon the light-sensitive cell 17, thereby causing a greater potential to be impressed across glow discharge device 11 than across glow discharge device 12. This increase in voltage across device 11 causes it to glow, whereupon the voltage across this device drops so that a greater part of the line voltage appears across glow discharge device 12 which in turn also glows, thereby allowing current to flow through both of the glow discharge devices. This current is sufficient to operate relay 14, thereby energizing the circuit to be controlled which may be, for example, a lamp circuit shown at 10. The relay 14 of the control circuit is energized as long as light from a source such as 20 does not impinge upon the light-sensitive cell 11. Such a circuit may be used to turn on lights when natural daylight falls below a certain intensity. Other applications such as counting systems, alarms, smoke detectors, sorting devices and the like may be controlled by this invention, as the mechanism would operate whenever the light beam from a source, such as 20, is intercepted by an object.

The arrangement described above may also be arranged to operate on direct current by removing the transformer 13 and connecting the glow discharge devices and relay directly to leads

9. In the direct current operation the balancing capacities 15 and 16 are not essential as there is no appreciable transfer of energy through the capacities of the component parts. In the direct current arrangement the glow in the discharge devices continues until the direct current is interrupted.

In Fig. 3, I have illustrated an embodiment of my invention which will indicate the presence of a passing body. Two glow discharge devices 21 and 22 are connected in series with the secondary winding of transformer 23 and the winding of relay 24. An alternating current potential is impressed across glow discharge devices 21 and 22 by means of transformer 23 which is connected to an alternating current line 25. Relay 24 may be used to control a circuit such as is indicated at 26. A metallic capacitor plate 27 is connected to one of the electrodes of glow discharge device 22 and a similar capacitor plate 28 is connected to the other electrode of the device 22. The capacitor plates 27 and 28 are arranged in the same plane, and to balance the effect of the capacity between these plates a capacitor 29 is connected across the glow discharge device 21. If a body 30 is moved in a plane parallel to that of capacitor plates 27 and 28, in the direction shown by the arrow, the capacity across cell 22 will be increased and thus the voltage balance across the glow discharge devices will be changed so that the cells are energized successively to operate the relay 24. This arrangement operates very readily when the body 30 is of a conducting material, and will also operate if body 30 is a non-conductor of sufficient magnitude and sufficiently near the plates 27 and 28.

A modification of Fig. 3 is shown in Fig. 4 which shows those elements which may be rearranged to obtain a more sensitive arrangement when capacitor plates 27 and 28 are to be used to denote the presence of a non-conducting body. In this figure similar parts are given the reference characters corresponding to those shown in Fig. 3. In this instance, however, the body 31 may be one of insulating or non-conducting material passed between capacitor plates 27 and 28 which are arranged in planes parallel to each other. The insulating or non-conducting body 31 is moved in the direction shown by the arrow to increase the capacity across glow discharge device 22, thereby disturbing the voltage balance across the glow discharge devices to such an extent as to energize them successively.

The arrangements shown in Figs. 3 and 4 may be applied to counting relays, sorting devices, safety devices, limit switches, automatic inspection devices and many other arrangements.

Another modification of my invention is illustrated in Fig. 5 in which I have arranged glow discharge devices 32 and 33 in series with relay 34 and the secondary winding of transformer 35, the primary winding of which is connected to the alternating current line 36. Relay 34 controls the energization of apparatus indicated by the rectangle 37. A capacitor plate 38 is connected to the electrode of discharge device 32 which is connected to the relay 34. A similar capacitor plate 39 is connected to the electrode of device 33 at the point where it is connected to the secondary winding of transformer 35. A third plate 40, similar to the plates 38 and 39 is connected to a point between the discharge devices 32 and 33. The capacitor plates are arranged in line in the same plane. This arrangement provides equal capacities across each of the glow discharge de-

5 vices 32 and 33. A series of capacitor plates of equal size and proportional to the capacitor plates 38, 39 and 40 are arranged in a plane parallel to these plates. The plate 41 is connected to plate 5 43 and is also connected to one terminal of the winding of transformer 44. The other terminal of this winding of the transformer is connected to the plate 42 which is arranged between capacitor plates 41 and 43. The primary winding of 10 transformer 44 is connected to a source of alternating current shown at 45 and a switch 46 is included in the circuit so that the transformer may be energized at will. If the capacitor plates 41, 42 and 43 are arranged in a plane parallel to 15 and opposite the plates 38, 39 and 40, an actuation of the switch 46 will impress upon these capacitor plates an alternating potential which will be transferred to the capacitor plates connected to the electrodes of the glow discharge 20 devices. This transfer of energy will unbalance the division of voltage across the glow discharge devices 32 and 33 and it is apparent that this will cause the glow discharge devices to be energized in succession in a manner similar to that 25 in the preceding figures. If the switch 46 is closed and the conductors or capacitor plates 41, 42, 43 are moved in the direction shown by the arrow, the voltages across glow discharge devices 32 and 33 will become unbalanced. In this arrangement 30 the distance between the two sets of capacitor plates may be greater, or the sizes of these plates may be considerably smaller than in the arrangement shown in Fig. 3 where the capacitor plates are not energized.

35 An arrangement of this kind may be applied to a communication system between an operator and trains. Such responses as the automatic operation of breaks could be obtained, as well as actuating warning signals in the cab of the train 40 operator.

45 Referring to Fig. 6 of the drawing, I have illustrated therein, a tuned radio circuit 47 provided with an antenna and ground and having its output connected to an electron discharge device 48. The electron discharge device 48 which may be 50 of the screen-grid type, is provided with a cathode, two control elements and an anode. The output of the radio circuit 47 is connected to one of the control elements and the cathode of the device 48. I have arranged two glow discharge 55 devices 49, 50 in series with the relay 51 and the winding 52 of transformer 53. Transformer 53 is connected to a suitable alternating current source by means of conductors 54. A winding 55 of the transformer provides a source of current for heating the cathode of device 48. The anode of discharge device 48 is connected to a point between glow discharge devices 49 and 50, and the remaining control element of discharge device 48 60 is connected to the electrode of glow discharge device 50 which is connected to the winding 52 of transformer 53. The relay 51 may be arranged to control any desired circuit.

65 In operation, the radio circuit 47 has high frequency current impressed thereon by means of the antenna, and the output of the radio circuit impresses a voltage upon the control element of discharge device 48 which effects a change in impedance of the discharge device. This change 70 in impedance unbalances the distribution of voltage across discharge devices 49 and 50 which causes them to be energized in succession, thereby allowing current to flow through the relay 51.

75 My invention therefore has the advantages: (1) that the controlling or relay circuit does not

consume energy unless a controlling operation is being performed; and (2) that an arrangement of simple apparatus inexpensive to construct and maintain provides a sensitive control apparatus.

While I have shown and described my invention in connection with certain specific embodiments it will, of course, be understood that I do not wish to be limited thereto, since it is apparent that the principles herein disclosed are susceptible of numerous other applications, and modifications which may be made in the circuit arrangements or in the instrumentalities employed without departing from the spirit and scope of my invention as set forth in the appended claims.

What I claim as new and desire to secure by Letters Patent of the United States, is:—

1. In a relay control circuit, a pair of glow discharge devices connected in series, a variable impedance connected in shunt to one of said devices, connections to said devices for supplying thereto a pulsating potential having a peak value substantially less than twice the break-down voltage of one glow discharge device and greater than twice the minimum glow voltage of one device whereby in response to a variation of said impedance said glow discharge devices break down and pass current, means responsive to current in said discharge devices, and means to vary said impedance during a normal condition of voltage across said glow discharge device sufficiently to cause said glow discharge device to break down and operate said current responsive means.

2. In a relay control circuit, a pair of glow discharge devices connected in series, a pulsating potential connected across said devices having a peak value substantially less than twice the breakdown voltage of a single glow discharge device, means for decreasing the potential across one of said glow discharge devices while the sum of the voltages across the two glow discharge devices is normal whereby the potential across the other of said devices become sufficient to cause breakdown thereof, and means responsive to breakdown of said discharge devices.

3. In a control circuit, a pair of glow discharge devices, a source of alternating potential connected to said devices so that the peak potential impressed upon each device is substantially less than the breakdown glow potential and greater than the minimum glow potential of said device, and light-sensitive means connected in said control circuit for successively increasing the potential across said devices whereby said devices are energized successively, and means responsive to the energization of said devices.

4. In a control circuit, a current responsive device and a pair of glow discharge devices connected in series, a source of alternating potential connected to said devices, said alternating potential having a value less than twice the breakdown glow potential and greater than twice the minimum glow potential of a single one of said devices, an impedance connected in parallel with one of said devices and a variable impedance connected in parallel with the other of said devices, means for changing said variable impedance during normal voltage conditions across said glow discharge devices whereby said glow discharge devices are energized in succession to pass current through said circuit.

5. In an electric circuit, the combination of a pair of glow discharge devices connected in series, a relay connected in series with said devices, a source of alternating potential connected to said relay and said devices, said source of alternating

potential having a peak value insufficient to cause said devices to become conductive, a group of capacity plates arranged adjacent to each other, one of said capacity plates being connected to a point between said glow discharge devices and the remaining capacity plates being connected to either side of said devices, a second group of plates arranged opposite said first group of plates, and means for applying a potential to said second group of plates whereby said glow discharge devices become conductive in succession to pass current.

6. In an electrical circuit, a pair of glow discharge devices connected in series, a control means connected thereto, a source of alternating potential connected to said devices and said control means of a value substantially less than twice the breakdown glow potential and greater than twice the glow potential of a single device, and light-sensitive means connected across one of said discharge devices for energizing said glow discharge devices in succession.

7. In combination, an electric circuit, means for closing said circuit, said means including a control circuit containing a relay and a pair of glow discharge devices connected in series, a source of alternating potential connected to said control circuit, the value of the potential being lower than that required to break down said glow discharge devices and produce a flow of current in said control circuit, means connected to said circuit responsive to the presence of an object for automatically increasing the potential across one of said discharge devices while the sum of the voltages across said glow discharge devices is normal thereby to produce a flow of current therethrough and to impress on said second glow discharge device a potential sufficient to produce a flow of current therethrough, whereby a current will be caused to flow through the control circuit to energize said relay.

8. In combination, an electric circuit, means for closing said circuit, said means including a control circuit containing a relay and a pair of glow discharge devices connected in series, a source of alternating potential connected to said control circuit, the value of the potential being somewhat lower than twice that required to break down a single glow discharge device to produce a flow of current therethrough and greater than twice the minimum potential necessary to maintain a glow in a single discharge device, means connected to said circuit responsive, during normal voltage conditions across said glow discharge devices, to high frequency current, said means automatically shifting the distribution of potential across said glow discharge devices whereby the potential impressed on one of said glow dis-

charge devices becomes sufficient to produce a flow of current therethrough, and the operation of said glow discharge device thereby increasing the potential across the other of said glow discharge devices to produce a flow of current therethrough, whereby a current will flow through said control circuit to energize said relay.

9. In combination, an electric circuit, means for controlling the closing of said circuit, said means including a control circuit containing a relay and a pair of glow discharge devices connected in series, a source of alternating potential connected to said control circuit, the value of said potential being less than that required to break down said glow discharge devices and produce a flow of current therethrough, and means connected to said circuit, including an electron discharge device responsive, during a normal condition of voltage across said glow discharge devices to high frequency current, said means in response to high frequency current automatically shifting the distribution of potential across said glow discharge devices to energize said devices in succession, whereby a current flow will be produced to energize said relay.

10. The method of controlling a circuit provided with a pair of glow discharge devices connected in series, which includes impressing on said glow discharge devices an alternating potential of a value substantially less than twice the breakdown glow potential and greater than twice the minimum glow potential of a single one of said devices, and successively energizing said glow discharge devices by increasing the potential across one of said devices while the sum of the voltages across said two glow discharge devices is normal, decreasing the potential across the other of said devices, and causing a flow of current in the circuit.

11. Means for operating an electric device comprising, a plurality of gaseous discharge tubes connected in series with said device and across a source of E. M. F. of a value less than the sum of the E. M. F.'s necessary to initiate a discharge in the individual tubes as long as the E. M. F. is distributed equally over the tubes, a photoelectric cell, and means associated with the photoelectric cell and the discharge tubes for altering the distribution of E. M. F. over the discharge tubes upon a change in light intensity at the photoelectric cell, whereby one discharge tube becomes a relatively good conductor and increases the potential across another discharge tube to a value whereat it also becomes a good conductor so that a comparatively large current flows through said discharge tubes and the electric device.

HARRY C. THOMPSON.
